UNITED STATES PATENT OFFICE.

KARL FRIEDRICH WILLKOMM AND CARL SCHUMANN, OF FREIBERG,
SAXONY, GERMANY.

ORE-CONCENTRATOR.

SPECIFICATION forming part of Letters Patent No. 313,145, dated March 3, 1885.

Application filed May 26, 1884. (No model.)

To all whom it may concern:

Be it known that we, KARL FRIEDRICH WILLKOMM and CARL SCHUMANN, citizens of Germany, residing at Freiberg, Saxony, in the 5 Empire of Germany, have invented a new and useful Improvement in Ore-Concentrators, of which the following is a specification.

Our improvement relates to the dry-process concentrators; and it consists in the peculiar 10 construction and arrangement of the parts composing the machine, as hereinafter particularly described, and pointed out in the claims.

In the accompanying drawings, Figure I is 15 a side elevation of our improved ore-concentrator. Fig. II is a top view of the same. Fig. III is a longitudinal section of the same. Fig. IV is a vertical cross-section at line Y Z, Fig. II. Fig. V is an end view of the apparatus, 20 and Figs. VI, VII, VIII, and IX are side view, end view, top-view, and cross-section of the air-nozzle F on enlarged size.

Similar letters represent similar parts in all the figures.

25 B is a suitable box or chamber, the bottom of which is made inclined toward one side, and divided in its lower part through suitable partitions, b, into a number of bins of suitable sizes, in which the concentrated ore is 30 collected. Suitable doors, N, Fig. I, are arranged in each bin for the purpose of removing the ore. At the after end of the chamber B a larger bin or chamber, C, is provided by means of the partition-wall b', extending near- 35 ly to the top of the chamber, and connected with the flue C', through which the air escapes. Near the forward end of the chamber B a hopper or receiver, A, is arranged to hold the pulverized ore, and provided at its bottom 40 with gates a a, to regulate the flow of ore from the receiver. At the front of the chamber A the air-pipes G G' are arranged. The lower pipe, G, is attached to the main air-pipe D, and is provided with a suitable cock, d, to 45 regulate or stop the passage of the air when desired. The upper pipe, G', enters the chamber B, and is provided at its end with the discharge-nozzle F. The lower end of this pipe G' connects with the lower pipe, G, by pass-

ing through a suitable stuffing-box, f, to allow 50 this pipe G', together with its discharge-nozzle F, to be moved upward or downward, so as to bring the discharge-nozzle F nearer to or farther away from the bottom of the receiver A. The upper end of the pipe G' is 55 for that purpose attached to a suitable sliding block, H, moving in guides fast to the outside of the chamber B, and connected to a screw, E, operated by a suitable hand-wheel, e, whereby this sliding block H, and consequently the 60 pipe G', with discharge-nozzle F, can be raised or lowered, as may be desired, to bring the current of air discharged at the mouth of the nozzle F nearer to or farther away from the under side of the receiver A. The regulating- 65 gates a a at the bottom of the receiver A consist of two valves, a a, hinged at the outer sides and meeting when closed in the central part. The spindles of these valves are provided with levers n n, and connected through rods m m and 70 rod v with a lever, M, by which arrangement the position of the valves a a can be regulated and the width of the discharge increased or diminished, as may be desired. The air- 75 discharge nozzle F consists of a cylindrical chamber, h, closed at the ends and provided with a large longitudinal opening, p, extending the whole length of the chamber h. The length of this opening, and consequently of the chamber h, should be in excess of the 80 length of the discharge-opening formed by the gates a a at the bottom of the receiver A. Upon the outer surface of this cylindrical chamber h two segments, k l, are fitted, hinged to the ends of the chamber h and capable of 85 turning freely. These segments are provided with straight flanges k' l', diagonally inclined toward each other, so that their outer ends meet and form a bell-shaped mouth, the inner end of which connects with the opening p in 90 the chamber h. One of these segments, preferably the lower segment, k, is provided with projecting side flanges, k'', between which the flange l works to prevent the escape of air at the sides. To each of these segments a pro- 95 jection, r r', is attached, connected to suitable screw-rods, s s', passing through the sliding block H to the outside of the chamber, and

operated by suitable hand-wheels, $x x'$. By means of these rods $s s'$ the segments $k l$ may be moved so as to increase the width of escape-opening at the extreme ends of the flanges $k' l'$, or to decrease the same, as may be desired. At the same time these segments may be moved to direct the current of air to any desired angle, as may be found most advantageous in regard to the nature of the ore under treatment.

10 The successful operation of this concentrator depends, according to the nature of ore under treatment, first, on the size of opening of the gates $a a$ at the under side of the receiver; second, on the quantity and force of the air; third, 15 on the angle at which the air strikes the falling mass of ore, and, fourth, on the distance at which the air-blast strikes the falling mass. All these may be easily changed and regulated by the several arrangements above described.

20 The falling pulverized ore is met by the air-blast of the required strength, volume, and the necessary angle, and is then carried through the chamber B, falling according to the gravity of its particles into the several partitions or 25 bins formed in the bottom of the chamber B, the lighter being carried the farthest. The fine dust will pass into the chamber C at the end, where it will collect, while the air escapes through the flue C'.

30 What we claim as our invention, and desire to secure by Letters Patent, is—

1. The herein-described ore-concentrator, comprising the chamber B, the lower part of which is divided into suitable bins by partition-walls b , and the end chamber, C, the receiver or hopper A, the regulating-valves or gates $a a$ at the under side of the receiver A, the air-pipes $G G'$, sliding block H, regulating-screw E, and end nozzle, F, with segments k and l , and means of operating the regulating-valves $a a$ and segments $k l$, the whole being arranged to operate in the manner and for the purpose substantially as described. 35

2. In an ore-concentrator, the herein-described discharge-nozzle F, consisting of the cylindrical chamber h , with longitudinal opening p , segments k and l , with straight flanges $k' l'$, and side flanges, k'' , on one of said segments, and projections $r r'$, in combination with screw-rods $s s'$, and suitable hand-wheels, $x x'$, for operating the same, substantially as 40 and for the purpose set forth. 45

In testimony whereof we have signed our names to this specification in the presence of two subscribing witnesses.

KARL FRIEDRICH WILLKOMM.
CARL SCHUMANN.
